UNITED STATES PATENT OFFICE

2,161,983

FORCED DRAFT REFRIGERATOR

Wilburn H. Swanson, Morrison, Ill., assignor to
Ice Cooling Appliance Corporation, Morrison,
Ill., a corporation of Delaware

Application October 6, 1937, Serial No. 167,486

11 Claims. (Cl. 62—72)

The present invention is related to refrigerators, and more particularly to those designed for domestic or household use where water ice or equivalent refrigerants are employed. The improvements, however, as herein delineated are susceptible to incorporation in refrigerators generally.

The invention has primary reference to refrigerators wherein forced draft is employed for effecting circulation of the air therein. An exemplification of such is found in Letters Patent of the United States No. 1,957,772 granted to Thomas B. Gilliam under date of May 8, 1934. The construction shown and described in that patent includes the usual type of cabinet but locates the food chamber in the upper portion thereof while the ice or cooling chamber is disposed therebeneath. The forced circulation of the air is effected by a motor-driven fan positioned at the upper portion of a flue that extends vertically of the cabinet, its upper end communicating with the food chamber and its lower end discharging at the bottom of the ice or cooling chamber at a point beneath a grid that supports the ice. This grid embodies a series of ducts or passages through which the relatively-warm air is caused to pass as the same is discharged from the lower end of the flue in order to produce a pre-chilling of the relatively-warm air before it enters the ice chamber where it is further cooled in its circulation over and about the ice.

It is the general object of the present invention to provide a refrigerator of the character referred to, the construction of which is such as to effect improved circulation of the air between and throughout the ice and food chambers so as to establish a more effectual distribution of the air, with a higher degree of uniformity in such distribution. This results in more economical consumption of the ice and improved preservation of the contents of the refrigerator.

A further object of the invention is the provision of improved means for accomplishing the pre-chilling of the relatively-warm air as it passes into the ice chamber so that the pre-chilling will lower the temperature of the air to a greater degree and thereby further effect greater economy in the ice consumption incident to the operation of the refrigerator.

Other objects and advantages will become apparent as the nature of the improvements is better understood, the invention consisting substantially in the novel construction, combination and arrangement of parts hereinafter fully described,

illustrated in the accompanying drawings, and finally pointed out in the appended claims.

The form of the invention herein delineated is regarded as a practical and desirable embodiment thereof, but it is to be understood that the same is susceptible to change, modification and variation as to the structural features and their relative arrangement. The present disclosure, therefore, is to be considered from the illustrative standpoint and not as imposing limitation or restriction upon the invention.

In the drawings,

Fig. 1 is a vertical transverse sectional view of a refrigerator constructed in accordance with the present invention, as on the line 1—1, Fig. 2;

Fig. 2 is a similar view, as on the line 2—2, Fig. 1; and

Figs. 3 and 4 are sectional plan views, respectively, as on the lines 3—3 and 4—4, Fig. 1.

Referring now in detail to the accompanying drawings, the numeral 10 designates generally the cabinet of the herein described refrigerator. Its construction may be that of the conventional cabinet of the present day type, including a top 11, a bottom 12, and side walls 13. It includes also an upper food chamber 14 and a lower ice or cooling chamber 15. The food chamber 14 and the ice chamber 15 are closed by appropriate doors 16 and 17, respectively. Generally speaking, the cabinet embodies likewise the usual metallic encasing shell for the insulation of the walls, top and bottom, and the customary metallic lining. The invention, therefore, is not limited to any specific construction of cabinet.

For separating the food chamber 14 and the ice chamber 15 a horizontally disposed partition 18 is located intermediate these chambers, which partition has an upstanding flange 19 at its side and rear edges. This flange is connected to the side and rear walls of the lining by seaming or other appropriate joint, as at 20. This supports the partition 18 in sustained relation with respect to the lining. At the front edge of the partition 18 an angular attaching flange 21 is provided, and this flange is suitably connected to a supporting cross bar 22 which extends crosswise of the cabinet, the flange 21 providing for the support of the front edge of the partition 18 and supplementing the flange 19 and the joint 20 to hold the partition 18 in place within the cabinet.

At approximately the mid portion of the partition 18 an elongated slot 23 is formed which is provided with a down-turned flange 24 that surrounds the edges of this slot. The slot 23 extends crosswise of the partition 18 in the general

direction of from the front to the back of the cabinet 10, and is of sufficient length and width to establish proper communication between the ice chamber 15 and the food chamber 14 to afford the requisite circulation of the air from the ice chamber 15 to the food chamber 14.

To effect forced circulation of the air within the cabinet 10 a pair of vertical extending flues 25 is employed. These flues are generally of triangular contour or configuration, and one is positioned in each of the rear corners of the interior of the cabinet. By such positioning of the flues 25 it will be apparent that a higher degree and more uniform distribution of the air within the cabinet is effected when the relation of these flues with respect to the air-circulating means is considered. These include a fan or blower 26, preferably of the squirrel-cage type, which is carried by a shaft 27 connected to the armature of an electric motor 28. The shaft 27 extends through a bearing head 29, so that said head is interposed between the fan or blower 26 and the motor 28 to separate the same. By reason of this the motor 28 occupies a position at the exterior of the food chamber 14 and does not affect the air of the chamber to increase the temperature thereof arising by operation of the motor. The bearing head 29 and the motor 28 are disposed within a supporting shell 30 having a flanged head 31 which fits within a rabbeted recess 32 formed in the upper portion of the rear wall of the cabinet. The supporting shell 30 is detachably held within the rabbeted recess 32 so as to be removed therefrom and introduced therein if it be desired to withdraw the motor and the fan from the cabinet, as in case of repairs or replacement. The shell 30, the bearing head 29, the motor 28 and the fan 26 thus constitute a unit which is complete in itself.

40 For the protection of the motor 28 a cover 31 encloses the same, and this cover is detachably connected to the supporting shell 30 so as to be movable therewith. A protective housing 33 also surrounds the fan or blower 26, the latter being eccentrically mounted in the casing 33, as appears from Fig. 1, the casing 33 having an inlet opening 34 for admission of air to the fan, and also a discharge opening 35 through which the air is blown by the fan.

50 Located in the upper end of the food chamber 14, and in communication with the upper ends of the flues 25, is an air-distributing chamber 36 which extends over the entire top of the food chamber 14, and said chamber 36 also has communication with the discharge 35 so that the air from the fan or blower 26 passes through said discharge 35 and into the distributing chamber 36. At a point immediately above the discharge opening 35 is positioned a V-shaped divider 37, which operates to separate the air blown from the fan and to deflect the body of air laterally in opposite directions, thereby directing the air thus discharged to the upper ends of the flues 25.

65 The casing 33, in turn, lies within a receiving housing 38 that depends from the air-distributing chamber 36 and is connected to the rear wall of the cabinet. The housing 38 has a plurality of louver openings 39 by which communication is 70 established between the food chamber 14 and the interior of the housing 38, the openings 39 serving for passage of the air as the same is drawn from the chamber 14 into the casing 33 under the action of the fan 26. It will be observed that the guards of the louver openings 39 extend up-

wardly so that the travel of the air into the casing 38 is over these guards and downwardly into the casing 38. Due to the casing 38 the air is not drawn directly from the food chamber 14 to the fan 26, but the flow is retarded, thus equalizing 5 the distribution of the air within the chamber 14 and increasing the refrigerating effect thereon on the contents of that chamber.

It will be understood that the chamber 14 is provided with such removable shelves as may be 10 necessary for supporting therein the articles to be refrigerated, and any shelving with the conventional supports thereof may be employed in this relation.

Within the chamber 14 is disposed a milk compartment 40, which is in the form of an elongated boxing, the forward end of which may be closed by a hinged door 41 to permit access to the interior of the boxing. The bottom of the latter, designated 42, may be of foraminous material so 20 as to permit the rising currents of cold air to enter the compartment 40 and contact the bottles of milk which may be placed therein. The side walls of the compartment 40 are also provided with a plurality of discharge openings 43 which 25 are arranged appropriately adjacent the upper and lower edges of the side walls. This provides for circulation of the cold air so that after it enters the compartment 40 through the foraminous bottom 42 it may escape through the side walls and enter the cooling chamber 14 so as to 30 refrigerate the contents thereof.

The compartment 40 is placed directly above the slot 23 of the partition 18. This directs the rising currents of cold air which pass through 35 the slot 23 directly to the foraminous bottom 42 for admission therethrough into the compartment 40.

It has been stated that one of the objects of the invention is the provision of improved means 40 for accomplishing the pre-chilling of the relatively-warm air as it passes into the ice chamber. To the accomplishment of this end a pre-chilling unit 44 is located in the bottom of the ice chamber 15 through which the relatively-warm air 45 passes after the same discharges from the lower ends of the flues 25. The unit 44 includes a lower water pan 45 of rectangular configuration in plan view, to which water pan a trap 46 is connected, said trap 46, in turn, being connected to a drain 50 pipe 47 through which the water of meltage will pass to the exterior of the cabinet. The trap 46 is so located in the water pan 45 as to maintain the ice water of meltage to the depth of about one-half inch. Thus, a substantial body of ice water 55 remains always in the bottom pan 45 in order to serve as a pre-chilling agent to the relatively-warm air which emerges from the flues 25.

The lower pan 45 has an imperforate top 48, save for an elongated slot 49 which extends laterally of the top 48, the edges of said slot 49 being surrounded by an upturned flange 50 which may be of a desirable height to maintain on the top 48 water of meltage resulting from the melting of the ice in the chamber 15. By reason of this construction the top 48 of the lower pan 45 is of a relatively low temperature and serves to lower the temperature of the relatively-warm air as the same enters the pan 45 from the flues 25. Due to the action of the trap 46 and the maintained 70 level of the water of meltage in the pan 45, a relatively large space exists between the surface of that water and the top 48. Hence, as the air passes through the pan 45 it is subjected to the low temperature of the ice water in the pan and 75

the low temperature of the top 48 induced by the water of meltage which stands on the top 48.

To support the ice on the unit 44 a grid 51 is included in this unit. The grid 51 comprises a plurality of fins 52 each of which is in the form of a flat strip the upper edge of which is turned downwardly to provide a flanged head 53 that is inclined to the body of the strip. This formation of the fins 52 imparts to the same relatively large cooling surfaces. As illustrated in Fig. 2 the ends of the fins 52 are received by flanged supporting members 54, the flanges of which embrace the upper and lower edges of the fins 52, the fins being suitably attached to the supporting members 54, and thereby held in spaced relation with respect to each other. The grid 51 is removably seated on the top 48 of the water pan 45 so as to be displaceable with respect to that pan. The ice, designated by the numeral 55, rests directly upon the fins 52 and the heads 53 thereof, so that the cooling effect of the ice is transmitted directly to the fins 52. The spacing apart of the fins affords passages therebetween through which the currents of air will rise as the currents pass through the slot 49. In this passage the bottom face of the ice will cause the air to be deflected laterally, and thereby the air currents will be brought into contact with the surfaces of the fins 52 and their flanged heads 53. Thus, the air, which has been pre-chilled in its passage through the lower water pan 45, will have its temperature further reduced. The air currents rise through the spaces between the fins 52, contacting the ice supported by the fins, and the maximum low temperature thus is imparted to the air currents.

As the slot 23 of the partition 18 constitutes the only communication between the ice chamber 15 and the food chamber 14, the flow of the air is retarded and the same held within the ice chamber 15 so as to effect the maximum heat exchange, and as the air thus cooled passes from the ice chamber 15 to the food chamber 14 it will be obvious that it presents to the contents of the food chamber 14 the maximum low temperature.

In the operation of the herein described refrigerator it will be understood that the motor-driven fan 26 will be controlled in its operation by suitable mechanism, whether manually operated or operated by the thermostatic conditions prevailing in the food chamber 14. Any suitable controlling mechanism of this sort may be employed. Obviously, thermostatic-controlled mechanism is preferable because responsive to the high and low limits of temperature which should characterize the normal conditions of the air within the chamber 14. Assuming that the ice chamber 15 is provided with the required ice or other refrigerant, and that the motor-driven fan 26 is in operation, the air within the food chamber 14 will be drawn through the louver openings 39 into the casings 38 and 33, and discharged by the fan 26 into the air distribution chamber 36. In the discharge of the air the divider 37 will separate the currents thereof so as to deflect these currents laterally in opposite directions. Inasmuch as the fan 26 creates a suction, the air within the ice chamber 15 is drawn upwardly through the opening 23 in the partition 18, and this suction extends further so as to draw the relatively-warm air from the lower ends of the flues 25 into the pre-chilling unit 44. With ice water in the lower pan 45 and on the top 48 of that pan, which top constitutes an upper water pan, the incoming currents of relatively-warm air pass

over and into contact with the water in the pan 45 and likewise the chilled top 48, with a resultant initial lowering of the temperature of the air by such contact. As the air is drawn upwardly through the slot 49 the same is distributed through the passages between the cooling fins 52, being further chilled by that contact, and then rises around the ice 55 so as to attain the maximum heat exchange. In the passage of the air through the slot 23 into the milk-cooling compartment 40 the contents of the latter are refrigerated, and as the air is discharged from the compartment 40 it enters the food chamber 14 to maintain the temperature of that chamber for preserving the contents thereof.

As above indicated, uniformity of temperature may be maintained in the food chamber 14 by utilizing thermostatic means for controlling the operation of the fan 26. By the employment of such means the operation of the fan will cease when the minimum low temperature has been attained, and when the maximum high temperature is reached the fan 26 will be caused to operate so as to change the temperature conditions within the chamber 14.

By locating the flues 25 in the rear corners of the cabinet, and dividing the air currents issuing from the fan casing so as to deflect the same oppositely in lateral directions, it will be apparent that the air is more effectually distributed with a higher degree of uniformity in such distribution, so that as the relatively-warm air enters the pre-chilling unit 44 from opposite ends of the same, the pre-chilling of the relatively-warm air likewise will be effected with a higher degree of uniformity. This results in more economical consumption of the ice, a more uniform meltage of the ice, and improved preservation of the contents of the refrigerator.

Moreover, by utilizing the construction which is embodied in the pre-chilling unit, the passage of the relatively-warm air between the ice water that is trapped in the lower ice pan 45 and the chilled top 48 of that pan, the pre-chilling action lowers the temperature of the air to a relatively high degree. In the further passage of the air through the spaces between the fins 52, and in contact with the relatively large surfaces afforded by the fins, there is a very decided further lowering in the temperature of the air before the same contacts with the ice supported by the grid. Obviously, therefore, in the contact of the air with the ice in this relatively low degree of temperature of the air, there is less consumption of the ice as the air is lowered to the maximum degree.

As the present invention is not concerned with the specific details of structure of the cabinet 10, no disclosure has been made of the sealing means for effecting tight joints between the doors of the food compartment 14 and the ice compartment 15 and other features by which the cabinet is rendered substantially air-tight and otherwise conditioned for proper use. These features remain to be supplied by the builders of the cabinet or cabinets in which the present invention is incorporated.

I claim:

1. In a refrigerator of the class described, the combination with a cabinet having a food chamber and an ice chamber in communication with each other, of a plurality of vertical flues arranged in said cabinet in separated relation and in communication with the ice chamber and the food chamber to conduct air from the food chamber

to the ice chamber, an air-distributing chamber arranged over the food chamber and in communication with the upper ends of said flues for effecting distribution of the air to the flues, and means for causing circulation of the air from the food chamber through said air-distributing chamber to said flues.

2. In a refrigerator of the class described, the combination with a cabinet having a food chamber and an ice chamber in communication with each other, of a plurality of vertical flues arranged in said cabinet in separated relation and in communication with the ice chamber and the food chamber to conduct air from the food chamber, to the ice chamber, an air-distributing chamber arranged over the food chamber and in communication with the upper ends of said flues for effecting distribution of the air to the flues, a pre-chilling unit associated with the ice chamber and with which the lower ends of said flues communicate, and means for causing circulation of the air from the food chamber through said air-distributing chamber to said flues.

3. In a refrigerator of the class described, the combination with a cabinet having a food chamber and an ice chamber in communication with each other, of a plurality of vertical flues arranged in said cabinet in separated relation and in communication with the ice chamber and the food chamber to conduct air from the food chamber to the ice chamber, an air-distributing chamber arranged over the food chamber and in communication with the upper ends of said flues for effecting distribution of the air to the flues, means included in said distribution means for dividing the air and deflecting the same to the respective flues, and means for causing circulation of the air from the food chamber through said air-distributing chamber to said flues.

4. In a refrigerator of the class described, the combination with a cabinet having a food chamber and an ice chamber in communication with each other, of a plurality of vertical flues arranged in said cabinet in separated relation and in communication with the ice chamber and food chamber to conduct air from the food chamber to the ice chamber, an air-distributing chamber arranged over the food chamber and in communication with the upper ends of said flues for effecting distribution of the air to the flues, means included in said distribution means for dividing the air and deflecting the same to the respective flues, a pre-chilling unit associated with the ice chamber and with which said flues communicate, and means for causing circulation of the air from the food chamber through said air-distributing chamber to said flues.

5. In a refrigerator of the class described, the combination with a cabinet having a food chamber and an ice chamber in communication with each other, of a plurality of flues arranged in opposite corners of said cabinet and in communication with the ice chamber and the food chamber to conduct air from the food chamber to the ice chamber, means in communication with the food chamber and said flues and intermediate the same for effecting distribution of the air to the flues, and means for causing circulation of the air from the food chamber to said flues.

6. In a refrigerator of the class described, the combination with a cabinet having a food chamber and an ice chamber in communication with each other, of a plurality of flues arranged in opposite corners of said cabinet and in communication with the ice chamber and the food chamber to conduct air from the food chamber to the ice chamber, means in communication with the food chamber and said flues and intermediate the same for effecting distribution of the air to the flues, and means for causing circulation of the air from the food chamber to said flues.

7. In a refrigerator of the class described, the combination with a cabinet having a food chamber and an ice chamber in communication with each other, of a plurality of vertical flues arranged in opposite corners of said cabinet and in communication with the ice chamber and the food chamber to conduct air from the food chamber to the ice chamber, an air-distributing chamber arranged over the food chamber and in communication with the upper ends of said flues for effecting distribution of air to the flues, means included in said distribution means for dividing the air and deflecting the same in opposite streams to the respective flues, and means for causing circulation of the air from the food chamber to said flues.

8. In a refrigerator of the class described, the combination with a cabinet having a food chamber and an ice chamber in communication with each other, of a plurality of flues arranged in opposite corners of said cabinet and in communication with the ice chamber and the food chamber to conduct air from the food chamber to the ice chamber, an air-distributing chamber arranged over the food chamber and in communication with the upper ends of said flues for effecting distribution of air to the flues, means included in said distribution means for dividing the air and deflecting the same in opposite streams to the respective flues, a pre-chilling unit associated with the ice chamber and with which said flues communicate, and means for causing circulation of the air from the food chamber through said air distributing chamber to said flues.

9. In a refrigerator of the class described, the combination with a cabinet having a food chamber and an ice chamber in communication with each other, of a plurality of flues arranged in opposite corners of said cabinet and in communication with the ice chamber and the food chamber to conduct air from the food chamber to the ice chamber, means for causing circulation of the air from the food chamber to said flues, and a pre-chilling unit associated with the ice chamber and with which said flues communicate, said pre-chilling unit including a pan for receiving the water of ice meltage, a top for said pan to be subjected to the cooling action of the water of ice meltage, said top having a flanged opening for passage of air therethrough, the flange of said opening serving to retain water of ice meltage on said top, the air from said flues being adapted to pass through said pan to be subjected to the water thereof and the reduced temperature of the top of the pan, whereby to initially cool the air drawn from said flues, and means for causing circulation of the air from the ice chamber to the food chamber.

10. In a refrigerator of the class described, the combination with a cabinet having a food chamber and an ice chamber in communication with each other, of a plurality of flues arranged in opposite corners of said cabinet and in communication with the ice chamber and the food chamber to conduct air from the food chamber to the ice chamber, means for causing circulation of the air from the food chamber to said flues, and a pre-chilling unit associated with the ice chamber and with which said flues communicate, said pre-chilling unit comprising a pan for receiving the water of ice meltage, and a grid disposed above said pan for supporting the ice in the ice chamber, the air from said flues being adapted to pass through said pan to be subjected to the water thereof, whereby to initially cool the air drawn from said flues, and means for causing circulation of the air from the ice chamber to the food chamber.

11. In a refrigerator of the class described, the combination with a cabinet having a food chamber and an ice chamber in communication with each other, of a plurality of flues arranged in opposite corners of said cabinet and in communication with the ice chamber and the food chamber to conduct air from the food chamber to the ice chamber, means for causing circulation of the air from the food chamber to said flues, and a pre-chilling unit associated with the ice chamber and with which said flues communicate, said pre-chilling unit comprising a pan for receiving the water of ice meltage, and a grid disposed above said pan for supporting the ice in the ice chamber, the air from said flues being adapted to pass through said pan to be subjected to the water thereof, whereby to initially cool the air drawn from said flues, and means for causing circulation of the air from the ice chamber to the food chamber.

opposite corners of said cabinet and in communication with the ice chamber and the food chamber to conduct air from the food chamber to the ice chamber, means for causing circulation of the air from the food chamber to said flues, and a pre-chilling unit associated with the ice chamber and with which said flues communicate, said pre-chilling unit comprising a pan for receiving the water of ice meltage, and a grid disposed above said pan for supporting the ice in the ice chamber, said grid including a plurality of separated fins forming passages therebetween for circulation of air therethrough, the air from said flues being adapted to pass through said pan to be subjected to the water thereof and through said passages between said fins to be subjected to the cooling temperature of said fins, whereby to initially cool the air drawn from said flues, and means for causing circulation of the air from the ice chamber to the food chamber.

11. In a refrigerator of the class described, the combination with a cabinet having a food chamber and an ice chamber in communication with each other, of a plurality of flues arranged in

opposite corners of said cabinet and in communication with the ice chamber and the food chamber to conduct air from the food chamber to the ice chamber, means for causing circulation of the air from the food chamber to said flues, and a pre-chilling unit associated with the ice chamber and with which said flues communicate, said pre-chilling unit comprising a pan for receiving the water of ice meltage, the top of said pan serving also as a pan for receiving the water of ice meltage, and a grid disposed above said top and supported thereby for supporting the ice in the ice chamber, said grid including a plurality of separated fins forming passages therebetween for circulation of air therethrough, the air from said flues being adapted to pass through said pan to be subjected to the water thereof and the reduced temperature of the top of the pan and also through the passages between said fins to be subjected to the cooling temperature of said fins, whereby to initially cool the air drawn from said flues, and means for causing circulation of the air from the ice chamber to the food chamber.

WILBURN H. SWANSON.
